UNITED STATES PATENT OFFICE.

JOHN WILLIAM PAULS, OF BUNDY, MONTANA.

CORN TESTER.

Application filed January 31, 1922. Serial No. 533,118.

To all whom it may concern:

Be it known that I, JOHN WILLIAM PAULS, a citizen of the United States, residing at Bundy, in the county of Musselshell and State of Montana, have invented certain new and useful Improvements in Corn Testers, of which the following is a specification, reference being had therein to the accompanying drawings.

10 This invention relates to a corn tester, and the object of the invention is the construction of a simple and efficient apparatus for testing seed corn, or any suitable seed, to determine their fertility.

15 With this and other objects in view, my invention comprises certain novel combinations, constructions and arrangements of parts as will be hereinafter described, illustrated in the accompanying drawings, and 20 more particularly pointed out in the appended claims.

In the drawings:

Figure 1 is a perspective view of an apparatus constructed in accordance with 25 the present invention, shown in an open condition, while

Figure 2 is a similar view of the apparatus, shown in a closed or rolled condition.

Figure 3 is a perspective view of one of 30 the division bars.

Figure 4 is a sectional view, taken on line 4—4, Fig. 3.

Figure 5 is a fragmentary, sectional view of the apparatus, showing a sprouting kernel of corn in one of the compartments.

Referring to the drawings by numerals, 1 designates a sheet of fabric, which is folded at 2 and stitched to strengthen the 40 edge. One end of the sheet 1 is fastened to the transverse wood strip 3, and the other end is provided with a flap 4, to which is secured the tie strings 5—5.

45 A metal cylinder 6 is employed around which the body of the device is wrapped (Fig. 2), and this cylinder is formed from a single piece of sheet metal, one edge 7 of which is placed against the sheet 1 that engages the wood strip 3 (Fig. 1), and this 50 edge 7 of the cylinder 6 is fastened to the strip by any suitable means; the other edge 8 of cylinder 6 is fastened by suitable means, such as tacks 9, to strip 3.

55 Spaced apart upon the inner face of sheet 1 are felt strips 10. Transversely arranged upon felt strips 10 are division bars

11. Each division bar is formed from a single strip of metal and is provided with a plurality of depending lips 12. Between each two lips 12 is a folded-in flange 13, 60 which flange 13 engages the top of a felt strip 10, preventing the division bar from cutting the felt strip when the apparatus is in its folded condition (Fig. 2). Each division bar is provided with rivet-receiving 65 apertures 14, through which rivets 15 extend; these rivets 15 also extend through the felt strips 10 and the sheet 1 fastening said bars, strips and sheet together. The lips 12 extend down between the felt strips dividing 70 the apparatus into compartments 16. On the top of the division bars I form numerals to designate the compartments and into each compartment I place the seed to be tested. For instance, put a kernel of corn 75 into the compartment designated by numeral "5", Fig. 1, and on the ear from which the particular kernel was taken fasten a suitable tag by a nail, on which tag is formed numeral "5"; do likewise with compartment "6" and another ear of corn, until the whole apparatus is filled with seed to be tested. After all of the compartments have been filled, then the apparatus is rolled together, as shown in Fig. 2, whereupon it is 80 put in a receptacle containing hot water and let stand for, say, twelve hours; then the apparatus is removed from the receptacle and permitted to drain, hanging in a warm room. The felt will hold the moisture until 85 the seeds sprout.

While I have described the preferred embodiment of my invention, and have illustrated the same in the accompanying drawings, certain minor changes or alterations 95 may appear to one skilled in the art to which this invention relates, during the extensive manufacture of the same and I, therefore, reserve the right to make such alterations or changes as shall fairly fall 100 within the scope of the appended claims.

What I claim is:

1. In an apparatus of the class described, the combination of a sheet, a strip extending transversely of one end of said sheet and 105 secured to the same, a cylinder forming strip coiled and straddling the end portion of the sheet having the transversely extending sheet secured thereon and having one end secured to the sheet and its other end 110 secured to the transversely extending strip, said sheet being adapted to be wrapped

about the cylinder forming sheet, and means for holding seeds in spaced relation upon said sheet.

2. In an apparatus of the class described, 5 the combination of a sheet, a transverse strip on said sheet, a coiled cylinder forming strip extending transversely of the sheet and having one end fastened to the sheet and its other end to said strip, and means on the 10 sheet forming seed-retaining compartments when the sheet is rolled around the cylinder.

3. In an apparatus of the class described, 15 the combination of a sheet, a transverse strip secured to one end of said sheet, a coiled strip forming a split cylinder and having one edge laid against the sheet and secured to the strip and its other edge secured directly to the strip, and means on the 20 strip for holding seeds in spaced relation when the sheet is wrapped around the cylinder.

4. In an apparatus of the class described, 25 the combination with a sheet, of spaced strips upon the sheet, and cross bars carried by said strips and having portions extending down between the strips and dividing space between the strips into seed-containing compartments.

5. In an apparatus of the class described, 30 the combination with a sheet, of relatively thick strips of absorbent material extending longitudinally on the sheet in spaced relation, and cross bars extending trans-

versely upon said strips provided with means extending between each two contiguous strips producing compartments for receiving seeds upon the sheet.

6. In an apparatus of the class described, 40 the combination with a sheet, of strips spaced apart upon said sheet, division bars resting upon said strips, each division bar provided with depending lips between the strips and with folded-in flanges between the lips, said flanges resting upon the strips, and means fastening the bars, strips and 45 sheet together.

7. In an apparatus of the class described, 50 the combination of a fabric sheet, felt strips extending longitudinally of the sheet and spaced apart thereon, division bars extending transversely of the sheet and strips engaging the upper faces of said strips, each division bar formed from a single piece of metal and including spaced depending lips 55 and spaced, in-turned flanges between the lips, said lips extending downwardly between the felt strips and said in-turned flanges resting upon the top of the felt strips, said bars provided with rivet-receiving apertures registering with the felt strips, and rivets in said apertures extending through the felt strips and sheet, fastening 60 said bars, felt strips and sheet together.

In testimony whereof I hereunto affix my signature.

JOHN WILLIAM PAULS.
